Grand Rapids, Minn.

Application June 20, 1947, Serial No. 755,820

5 Claims. (Cl. 25—41)

1

This invention relates to concrete block machines and has special reference to that type which molds a cement aggregate into formed building blocks for subsequent setting and drying.

The principal object of this invention is to provide a machine of compact construction capable of conducting the entire block-making process in automatic sequence, thus enabling a sole operator to make disposition of a completed block while the machine is producing another. In this manner a maximum of efficiency is attained.

Another object of this invention is to provide a block-making machine wherein a high personal safety factor can be had. In the practice of the invention, it is possible to produce cement blocks at the rate of six or more per minute. During most of this time the operator is engaged in simply initiating each block-making process of the machine and then disposing of the finished block while the machine is operating.

Another object is to provide a novel automatic clutch mechanism particularly applicable to the continuity of the operation of the device after being initially tripped.

Another object is to provide for most efficient tamping of the ultimate blocks whereby optimum results will be obtained.

Still another object is to perform all timing of the operations of the machine automatically to avoid the errors of human judgement which occur in manually controlled devices. For example, when a manually controlled clutch is used to move the sliding hopper of such a machine, it often happens that the operator misjudges the positioning thereof which requires a return of the hopper to starting position and a new try to position same, this being a waste of time.

Other objects and advantages will appear as the description of the invention progresses.

In the accompanying drawings forming part of this application wherein like reference numerals indicate like parts:

Fig. 1 is a front elevational view of one of the completely assembled machines with a finished block awaiting removal therefrom.

Fig. 2 is a side elevational view of Fig. 1 with the finished block removed and parts broken away for better comprehension.

Fig. 3 is a somewhat enlarged broken plan view of the block mold table and the starting clutch mechanism.

Fig. 4 is an enlarged fragmental perspective view of the tamper control mechanism.

Fig. 5 is an enlarged front elevational view partly broken away of one of the novel clutches.

2

Fig. 6 is a side elevational view of Fig. 5.

Fig. 7 is an enlarged diagrammatic view of the tamper starting mechanism.

Fig. 8 is a plan view of the block lift operating mechanism.

Fig. 9 is an enlarged isometric view of a portion of the automatic trip mechanism for return of the sliding hopper.

Fig. 10 is an elevational view of the pawl and ratchet attachment of the tamper control mechanism.

Fig. 11 is an enlarged isometric view of the pallet lifting rack.

Fig. 12 is an enlarged side elevational view of the safety slip clutch.

Fig. 13 is a side elevational view of one of the tampers.

In the drawings, the reference numeral 1 represents the rectangular base of the framework 20 of the block machine. This rectangular base is constructed of angle iron, as is all the framework unless otherwise specified. In most cases, the unions are accomplished by welding; and where not welded bolts are employed to make for ready 25 replacement should parts wear.

The reference numerals 2 and 3 represent parallel, vertically spaced channel-iron standards considerably heavier than other parts of the framework, for about these standards occur the violence of and the heavy mechanism for the tamping operation. The allied members of the frame-work include the tamper-guiding channel irons 4, 5, 6 and 7 bolted horizontally transverse 30 to the standards 2 and 3. The motor mount 8 is installed at the rearward, lower end of the framework.

Mounted fixedly and centrally within the framework is the block mold table 9, seen as installed in Figs. 1 and 2 of the drawings. Also 40 shown in Figs. 1 and 2 are two hoppers, the main or supply hopper 10 and the horizontal reciprocable hopper 11 slidable longitudinally upon the upper surface of the table 9. The table 9 has three principal functions, to wit: (1) support a block form 12, (2) provide a support and surface for the sliding hopper 11, and (3) provide ample support for the finished blocks.

As seen in Fig. 2, the sliding hopper 11 includes a compartment 17 for receiving a measure of the 50 aggregate contained in the main hopper 10, said compartment 17 being of a size to hold the correct amount of aggregate for deposit into the mold 12 after which an immediate tamping process follows. It is noted that the trailing portion of the hopper 11 provides a flat upper surface 18 in

the same plane with the upper edges of the compartment 17 so as to act as a closure during the forward movement of the sliding hopper for the main hopper 18.

The mold formed in the forward portion of the table 9 is, of course, the stationary block form which contains the aggregate during the all-important tamping process. This block form is in itself bottomless, save a plurality of transverse, semi-inverted angle irons 13. The angle irons are so inverted so as to easily shed strayed aggregate. The principal function of these angle irons 13 is to support the three aligned cores 14, and the half core 15 at either end of the block form, more clearly shown in Fig. 3, and to form a substantial base upon which the pallet 16 as seen in Fig. 2 is received.

This pallet is placed manually by the operator into the block form prior to the making of each block and is so designed to snugly fit and conform with the walls and core-contours of the block form. It is obvious that the cores shown create the usual design of one common type of cement block, and that the form may be altered in size for making different sized blocks. The cores, obviously, would have to be altered and corresponding pallets and tampers would have to be used.

Mounted vertically and equally spaced between the standards 2 and 3 and guided by the transverse channel irons 4, 5, 6, and 7 are four vertically reciprocable tamper stems 19, 20, 21, and 22 each carrying at its respective lower terminus a tamping head 23. (The term "tumper" shall be meant hereinafter to comprise the tamper stem and the tamper head.)

Mounted transversely a predetermined distance above the transverse channel irons 4 and 5 is another channel iron 24 having a hardwood shock-absorbing strip 25 bolted removable thereupon for replacement should same wear. This combination, members 24 and 25, determines the lower limit of stroke of the tampers by means of engagement with a rearwardly projecting arm or stop 26 integral with each respective tamper stem. The spaced relationship of the tampers and the correct guidance thereof is achieved by the members 27 transverse the channel irons 6 and 7, and 28 transverse channel irons 4 and 5. The tamper heads are bolted as at 29 to their respective tamper stems, the employment of bolting means being for replacement by larger heads in the instance of the block mold being enlarged for larger block-making; and they are shaped to conform with the cores 14 and 15 to tamp there-around.

The entire machine is powered by a single preferably one and one-half horsepower electric motor 30 although a motor of but one horsepower is sufficient as has been proved by practice. The power is increased and the speed is reduced by a series of reduction pulleys and sprockets, the first of these being, of course, the motor pulley 31 communicating with a considerably larger pulley 32 by means of a V-belt. This second pulley 32 is fixed upon one end of a transverse shaft 33 suitably mounted upon either side of the framework of the machine. The sole function of this shaft is to provide a substantial bearing for the pulley 32 and to continue speed reduction by providing at the extreme terminus thereof outside of the pulley 32 a relatively small chain sprocket 34 operating by means of chain 35 the larger sprocket 36 fixed to the extreme terminus of shaft 37, which latter is mounted

transverse the upper forward end of the machine framework and bears upon both sides thereof.

Not only does shaft 37 provide a substantial bearing for sprocket 36 but it also carries means to operate the tampers. The tamper-operating means embodies four kickers or lifts 38 fixed radially upon said shaft 37 and rotatable therewith with each in line with its respective tamper stem. These tamper lifts extend alternately upon opposite sides of the shaft 37 as seen in Fig. 1 to create a perfect counter-balancing effect, thus eliminating undue vibration.

The lifts 38 are of U-shape and intermediate the spaced extremities of each lift is rotatably mounted a roller for rolling engagement with the arms 26 of the tampers during the upward swing of the lifts. These lifts are continuously swinging 360 degrees during the operation of the machine; and each time shaft 37 completes a revolution, which shaft as stated is continuously revolving, each of the four lifts has completed a raising of its respective tamper which drops to tamp by gravity.

The counterbalanced positioning of the tamper lifts upon said shaft 37 has obviously an alternating effect upon the tampers, which is of major importance; because, it has been found that alternating impact of the tamper heads upon the aggregate in the block form results in a firmly and uniformly packed block. It has also been found that not only are ten strokes of each tamper sufficient, but that allowing more than ten strokes would be folly; for over-compression has degrading effects upon the finished block. In the light of such experience, we have provided the machine with means which permit ten and only ten strokes of each tamper and means to retain the tampers in their upward positions, as shown in Figures 1 and 4 of the drawings.

Normally, the tampers are retained in their upper inactive positions until needed and after tamping ten strokes are caught and again retained in inactive position. Means for carrying out the above is as follows:

Mounted rearwardly and transverse the standards 2 and 3 is a horizontal line of shafting indicated at 39. At one end of said shaft 39 is mounted a relatively large timing ratchet 40. This timing ratchet has the proper number of teeth with two thereof having been removed as at 41 to provide an idling action for the pawl 42 and consequently cease intermittent rotation of the shaft 39 by said pawl. The pawl 42 is continuously reciprocated by means of action of the short crank arm 43 fixed to the terminus of shaft 37 which, as stated above, is rotating continuously. The contractile helical spring 44 intermediate the pawl and the framework, along with the pawl guide 45, insures constant contact and guidance of said pawl against the timing ratchet. Obviously then, the shaft 39 will be rotated intermittently by the pawl 42 until the latter slips on the surface provided by the missing teeth. It is noted that the clicking brake member 46 prevents any possibility of reverse action of the timing ratchet.

At the opposite end of said shaft 39 is fixed a cam 47 which will be described in detail hereinafter. It is to be noted that this cam 47 is completely dependent upon the pawl 42 and ratchet 40 at the opposite end of shaft 39, and their association with the accomplishment of retaining the tampers after a predetermined number of strokes resides in another transverse rockable shaft 48 carried intermediate of two for-

wardly extending block-like supports 49 fixed to the upper face of the standards 2 and 3.

This shaft 48, adjacent each terminus, is carried eccentrically by the bushings 50 of each of the supports 49. Aligned with each tamper, of which there are four, is a tamper-catching finger 51 carried loosely upon said shaft 48. The function of these fingers is to, when biased rearwardly, lock themselves in their respective tamper-catches 52 fixed to each tamper stem.

The arms 53 are of U or clevis shape, the two lower-most termini thereof having aligned bores therethrough for swingable carriage by said shaft 48. Each finger 51 is screw-threadedly carried by the arm 53 and is so carried that it may be replaced should same wear. The uppermost extremities thereof are of chisel shape to insure such flawless catching action.

Fixed to the shaft 48 and centrally of their respective arm termini, are straight radial arms 54 which serve a dual function: (1) being rigidly fixed upon shaft 48 retain the fingers 51 in alignment with their respective tamping shafts and (2) serve to bias the fingers to closed, catching positions, or to free open position.

The yieldable biasing of the fingers 51 by each arm 54 is accomplished by the forwardly and downwardly arcuate prong 55 fixed to and extending from the face 56 of each arm 53 which passes through the guiding hole 57 near the extremity of said arm 54. The prong 55 acts as a core for the two helical expansive springs 58 and 59, the one 58 intermediate the arm 53 and the arm 54, and the one 59 between said arm 54 and the terminus of said prong 55.

Fixed to shaft 37 and inwardly of the sprocket 36 is a smaller sprocket 60 operating directly in line therebelow a clutch 61, centrally of the machine, and a transverse shaft 62 mounted upon the rearward base of the framework by means of the long chain 63 engaging the sprocket 64 of said clutch 61 and the sprocket 65 of said shaft 62.

The clutch 61, typical of those used in two other instances in the machine, is important to the accomplishment of the automatic sequence mentioned above and is shown in detail in Figs. 5 and 6. The clutch in itself embodies the ring-like sprocket 64 which rides loosely upon shaft 66 which latter carries fixedly thereupon the central mechanism for intermittent engagement with the inner ratchet ring 67 of the sprocket 64. Means for said engagement comprises the cross arm member 68 fixed to the shaft 66. At one end of the cross arm the swingable pawl or arm 69 is attached as at 70 for engagement with the internal ratchet 67 of the sprocket 64. The expansive helical spring 71 at the opposite end of the cross arm biases pawl 69 towards engaging position with the ratchet 67 and only when pressure is applied in the direction "A" to trigger 72 which is rigidly fixed to the free end of the pawl will the clutch be disengaged and be in idling status.

One use of the type clutch above described is found in the reciprocation of the sliding hopper 11. As seen in Fig. 8 shaft 62 carries fixedly therewith the like sprockets 73 and 74 the one 73 for operation of the sliding hopper-reciprocation clutch 75, shown in Fig. 3, and the one 74 for operation of the block lift clutch 76, said clutches being operated by means of suitable sprocket chain connections.

When clutch 75 is engaged for operation in the same manner as clutch 61 is engaged, the shaft

77 is rotated, revolving therewith crank arms 78-78 at either end of shaft 77. The crank arms 78 render a piston-like action to the horizontal levers 79 disposed longitudinally on either side of table 9, which in turn, are pivotally connected as at 80 to the upright levers 81 pivoted as at 82 to the base of the framework, and operate the sliding hopper 11 by means of the pivotal connection 83 of levers 81 therewith.

10 Obviously, when the machine is idling, shafts 33, 37, and 62 are rotating; the tamper lifts are revolving; and clutches 61, 75, and 76 are in disengaged status. Assuming the machine to be in idling status and the main hopper 10 supplied with the desired amount of aggregate, the compartment of the sliding hopper 11 is normally under the discharge orifice of the main hopper and contains the correct amount of aggregate from the main hopper for deposit into the block form 12 in the table 9.

15 To initiate the block-making function of the machine the operator simply pulls the knob 84 of the clutch trip rod 85 which lies longitudinally of the table 9 below the pallet-receiving angle irons 13 of the block form 12. This rod 85 is connected to stem 90 of the stopper 91 within the housing 87, which stem and stopper are biased rearwardly into clutch trigger-catching position by the helical expansive spring 86 within the 20 casing 87 which is bifurcated at one end thereof as at 88 adjacent the trigger 89 of the clutch 75 to allow said trigger 89 to pass thereby only when stopper 91 is pulled forwardly by the operator's pull on rod 85, attached to said stopper. With 25 no contrary pressure on trigger 89, the clutch 75 is engaged, as is the case with clutch 61, thus transmitting power to shaft 77.

20 Shaft 77 completes exactly one-half revolution when started which by means of the combination 40 of levers 78, 79, and 81, push the sliding hopper forward into position over the block mold 12 in the forward end of table 9. As stated above, shaft 77 completes exactly one-half turn, this being accomplished by means of a second tripping arrangement 92 exactly like the one 81, and in 45 180 degrees about the axis of shaft 77. This tripping means 92 engages trigger 89, thus disengaging the clutch 75, which automatically halts shaft 77 and, of course, retains the hopper 11 in position over the block form 12. As stated previously, the upper surface of the trailing portion of the sliding hopper slides snugly in place under the orifice in the bottom of the main hopper 10 closing same. For guidance during the forward and 50 rearward movements of the sliding hopper, depending lugs 93 of which there are four, two on each side, slide against the upper side edges of the table 9.

55 With the sliding hopper in place over the block form and the latter filled with aggregate, the next step of the automatic sequence is the starting of the tampers. This is accomplished upon the forward movement of the sliding hopper which trips clutch 61 in the same manner as clutch 75 is tripped, in this case, the lateral projection 94 on the side of the sliding hopper 11 strikes the trip 95 which swings the arm 96 thereby pulling the trip mechanism 97 similar to that heretofore described. Upon release of the trigger 72, the 60 clutch 61 rotates until stopped again by the tripping mechanism 97. As the sliding hopper 11 returns, the lug 94 passes the trip 95 and has no effect thereupon, the action being similar to the trip mechanism shown in Fig. 9.

65 With the engaging of clutch 61, shaft 66 is

rotated, and carried upon shaft 48 is the crank arm 98, see Fig. 7, which operates the diagonal rod 99 pivoted to the upper terminus 100 of the bifurcated lever 101 loosely mounted upon the stub extension of shaft 39. This bracketed extension obviously being simply to accommodate the full swinging of the weighted arm 102 fixed to the shaft 48, see Fig. 4. Centrally of the bifurcated lever 101 is mounted a notched cam 103 fixed to the stub extension of shaft 39. The action of the lever 101 upon said extension 39 is by means of the dog 104 installed longitudinally and centrally within the lever 101 biased towards the cam by the expansive helical spring 105. Obviously then, when the clutch 61 is engaged, crank arm 98 is swung counter-clockwise, as viewing Fig. 7, and pulls down rod 99 which in turn pulls upon lever 101 which, by means of the dog 104 and the notch 106 in cam 103, rotates shaft 39 by virtue of their cam and bracket connection. At the opposite end of the shaft 39, as previously explained, the ratchet wheel 40 which is rotated with the shaft 39 to a point where pawl 42 may begin to take effect in completing the rotation of shaft 39, see Fig. 10.

When cam 47 on shaft 39 is thus effected by action of the remote clutch 61, it is partially rotated carrying the weighted arm 102 upwardly on the ball bearing roller 107 from the idle or inactive position in the lowermost area of the cam undulations as shown in dotted lines Fig. 4, to the outer circular edge 108 of the cam 47. As the arm 102 is raised, the shaft 48 is rocked slightly to tilt the fingers 51 out of engagement with the catches 52 allowing the tampers to drop where they may be acted upon by the tamper lifts 38 to perform the tamping operation.

After the tampers have completed ten strokes the roller 107 has traversed the outer circular rim of the cam 47 and reaches the position shown in Fig. 4. As the arm 102 goes downwardly into the undulated portion of the cam 47 upon the eleventh stroke of the pawl and ratchet, the shaft 48 is again rocked, this time tilting the fingers 51 into position to engage the catches 52 and stop further tamping operation. Upon the succeeding actions of pawl 42, the cam 47 is rotated so that roller 107 reaches the idle or inactive position shown in dotted lines Fig. 4 and by the falling of the arm 102 the tampers are raised sufficiently to prevent the tamper lifts 38 from engaging their respective tamper arm 26 until clutch 61 is again engaged by the second block-making cycle. This also raises the tamper heads sufficiently to permit of movement of the sliding hopper without interference therefrom.

Having the aggregate tamped and molded in the block form, the sliding hopper 11 is then automatically retracted, shearing off the excess aggregate from the block and carrying back the same therewith, leaving a smooth, flat block surface flush with the upper surface of the table 9. Means for accomplishing the same is as follows:

Fixed to shaft 48 adjacent the standard 2 is a trip arm 109 for engagement with a trip lever 110 pivotally carried upon the shaft 111 journaled upon the frame member 2. Upon the opposite end of this shaft is fixed crank arm 112 to which is attached the sliding hopper trip rod 113 extending diagonally to the rear of the machine where it activates the crank arm 114 fixed to the transverse shaft 115, see Figs. 3, 4, and 9. Shaft 115 carries the depending crank arm 116 which, when shaft 115 is rotated by indirect action of trip arm

109, pulls trip 117 of the tripping mechanism 118 identical with the clutch-engaging means within the housing 87 and alternately operable therewith. When clutch stopper 119 is retracted, trigger 89 is freed; thus allowing shaft 77 to complete a second half revolution terminated by contact of trigger 89 with stopper 91 of the tripping mechanism within the housing 87.

An opposite action of members 78, 79, and 81 is produced by the second one-half revolution of shaft 77; and of course, the opposite action results in the retraction of the sliding hopper 11 into position under the main hopper so that compartment 17 thereof and the discharge orifice of the main hopper register where it is again filled with the correct measure of aggregate for the making of the next block.

As the sliding hopper is about one-half its way back to fully retracted position, the completely molded cement block and its supporting pallet is raised where it may be placed upon a stripping arm-like carriage. Means for accomplishing this final automatic operation is as follows:

As stated above, clutch 76 automatically operates the block-lifting mechanism. Clutch 76, being powered continuously during the idling of the machine by the chain 121 from the sprocket 74 on the shaft 62, is engaged as by the crank arm 122 on shaft 77 which, during the final one-half revolution of shaft 77 trips lever 123, pivoted as at 124, which in turn acts upon trip mechanism 125 to engage clutch 76 in a manner identical with the engaging of clutch 75. When clutch 76, mounted upon transverse shaft 126, is revolved one-half turn, determined by the stopper of the tripping arrangement 127 directly opposite the tripping arrangement 125 in a manner similar to that which accomplishes the sliding of hopper 11, the shaft 126 carries at either end thereof the crank arms 128 as seen in Fig. 8, which activate the long arms 129 pivoted at the rear ends thereof to the framework as at 130, in an upward and downward motion as by the link arms 131.

Mounted beneath the block form 12 and vertically reciprocable therewith, is a rectangular block-lifting frame 132 carrying screw-threadedly adjustably therein the four vertical pallet-engaging and raising rods shown at 133.

This frame 132 is carried vertically slidably below the block form by means of the grooved guides 134 fixed at either end thereof for sliding guidance about the vertical members 135. Carried by the grooved guides 134 are two inwardly projecting stub shafts 136 for engagement within the slots 137 in the termini of long arms 129. From the above it is obvious that the engaging of clutch 76 will raise the pallet-engaging rods 133, and in doing so will raise the finished block up from within the block form 12 and will retain same there, for, as stated, the trip mechanisms will allow but one-half turn of said shaft 126.

The ultimate removal of the finished block is achieved by the take-off mechanism comprising the arm 138 and the bumper 139 fixed upon the vertical shaft 140. This combination is secured in hinge-like fashion to the framework of the structure as at 141 and is manually swingable by means of handle 142. The arm 138, supported by the brace 143, has fixed thereto two parallel block-carrying fingers 144; and when the arm 138 is swung into the machine, the block carrying fingers 144 are inserted intermediate the block table surface and the raised pallet 16 and the finished block.

When arm 138 is swung inwardly, the bumper

arm 139 is swung therewith, engaging the lever 145 pivoted centrally thereof as at 146, the opposite end thereof being pivoted to the retraction arm 147 of the tripping arrangement 127. When the clutch 76 is thus again engaged, the shaft 126 completes its revolution determined by its being stopped by the tripping mechanism 125. Obviously, when shaft 126 completes its second one-half revolution, the combination of crank arms 128 and long arms 129 lowers the block lift to a position below the block form, its lowermost position determined by the cessation of the rotation of shaft 126 when clutch 76 is disengaged by tripping means 125.

When the block lift is lowered, it naturally places the finished block upon the fingers 144 of the arm 138, whereupon the operator manually pulls the handle 142 swinging the block away from the machine where it may be manually disposed of.

To make another block, the operator simply initiates the operation by pulling tripping knob 84, and the entire function, as described above, is repeated.

From the above, it is apparent that, in view of the automatic sequence of the operation and the two simple manual operations somewhat physically remote from the mechanism of the invention, we have devised a block-making machine wherein a high safety factor is maintained.

As automatic safety means should aggregate or other foreign objects interfere with the sliding hopper or mechanism therebelow, we have provided a slip clutch comprising the toothed member 148 integral with sprocket 65 carried loosely upon shaft 62 and biased by the relatively strong expansive helical spring 149 against the opposed similarly toothed member 150 fixed to said shaft 62.

Having thus described our invention, what we claim is:

1. A machine for making concrete blocks comprising: a frame, a block mold table within said frame, a block form in the forward end of said table, a minor hopper slidably longitudinally on said table, a supply hopper directly above said minor hopper for filling same, tampers supported above said form, control means for intermittently operating said tampers, a clutch manually engageable to move said minor hopper forward to discharge its contents into said form, tripping mechanism operated by said control means to engage said clutch to return said minor hopper to its rearmost position, a block lift operating clutch carried in the lower portion of said frame, block lift mechanism intermittently operable by said clutch, and tripping mechanism activated during the return of said minor hopper to engage said block lift clutch to lift the finished product out of said form by said block lift mechanism.

2. The structure as set forth in claim 1 and said means for operating said tampers compris-

ing: a driving shaft; tamper arm engaging lifts fixed radially on said shaft, one for each of said tampers; an eccentrically mounted rockable shaft; tamper catching fingers carried by said rockable shaft in line with each of said tampers; a weighted arm fixed to one end of said rockable shaft; a roller on said arm; an intermittently operable shaft; an undulated cam fixed adjacent the end of said intermittently operable shaft, said roller riding on the periphery thereof to rock said rockable shaft to release said fingers; a ratchet wheel fixed to the opposite end of said intermittently operable shaft; a crank arm fixed to the end of the said driving shaft adjacent said ratchet; and a pawl operated by said crank arm to rotate said ratchet, intermittently operable shaft, and undulated cam so constructed and arranged that when said tampers are released by said fingers, said tamper arm engaging lifts raise said tampers a predetermined distance where they are dropped by gravity to tamp.

3. The structure as set forth in claim 1 and means for starting said tampers comprising: a shaft, a cam fixed to said shaft, a lever biased towards engagement with said cam, an undulated cam fixed to said shaft inwardly of said first mentioned cam, a rockable shaft eccentrically journaled adjacent said first mentioned shaft, tamper catching fingers carried on said rockable shaft aligned with each of said tampers, a weighted arm fixed to said rockable shaft, a roller carried on said arm outwardly thereof and riding on the periphery of said undulated cam and resting normally on the innermost of said undulations, so constructed and arranged that downward movement of said lever rotates said shaft so as to carry said roller to the outermost extremities of said undulated cam thereby rocking said rockable shaft to release said fingers from engagement with said tampers.

4. The structure as set forth in claim 1 and take off mechanism adapted to be swung under said finished product and above said mold to receive said block from said block lift mechanism.

5. The structure as set forth in claim 4 and means operated by said take off mechanism as it is swung under said finished product to engage said block lift clutch for returning said block lift mechanism to starting position.

JACOB MAKEDONSKY.
